SKYLIGHT CONSTRUCTION

Filed Dec. 8, 1920

2 Sheets-Sheet 2

UNITED STATES PATENT OFFICE.

JOSEPH SYLVAN, OF CHICAGO, ILLINOIS.

SKYLIGHT CONSTRUCTION.

Application filed December 8, 1920. Serial No. 429,077.

To all whom it may concern:

Be it known that I, JOSEPH SYLVAN, a citizen of the United States, and a resident of Chicago, in the county of Cook and State of Illinois, have invented certain new and useful Improvements in Skylight Constructions; and I do hereby declare that the following is a full, clear, and exact description thereof, reference being had to the accompanying drawings, and to the letters of reference marked thereon, which form a part of this specification.

This invention relates to improvements in skylight construction and consists of the matters hereinafter described and more particularly pointed out in the appended claims.

One of the objects of the invention is to provide a strong, rigid and leak proof skylight construction, which will readily catch all water of condensation which forms on the inner surface of the skylight and will discharge the same outside of the skylight so that there will be no dripping of water into the room beneath the same. Another object of the invention is to so arrange and construct several of the non-sustaining parts of the skylight, that they may be quickly removed without the aid of tools, for the purpose of fully exposing all parts of the skylight when it is desired to paint the same.

A further object of the invention is to so arrange the several parts that they interengage each other in a manner locking said parts in place.

The many advantages of the invention will more fully appear as I proceed with my specification.

In the drawings:

Figure 1 is a top plan view of a building skylight, embodying my improved construction.

Figure 2 is a transverse vertical section through the skylight on an enlarged scale, in a plane indicated by the line 2—2 of Figure 1.

Figure 3 is a view similar to Figure 2, on a further enlarged scale, the plane of the section being taken on the line 3—3 of Figure 1.

Figure 4 is a longitudinal detail, vertical sectional view taken on the line 4—4 of Figure 3.

Figure 5 is a detail sectional view taken on the line 5—5 of Figure 4.

Figure 6 is a detail perspective view of a condensation gutter member, embodied in my improved skylight construction.

Figure 7 is a cross section of a combination sealing and gutter strip embodied in my improved skylight construction.

Figure 8 is a cross section through a one piece ridge strip embodied in my improved skylight construction.

Figure 9 is a cross section through an eaves gutter strip embodied in my skylight construction.

Referring now in detail to that embodiment of the invention illustrated in the accompanying drawings, 10 indicates a building roof having an upright curb wall 11, defining an elongated rectangular skylight opening 12. The framework of the skylight includes longitudinally spaced cross beams 13, of angle bars which rest at their ends upon the curb wall, at points spaced from the upright end plates 14 of the skylight (see Fig. 1). 15—15 indicates the rafters of the skylight which are inclined downwardly and outwardly from each other from the ridge or peak of the skylight, the outer ends of said rafters being fixed to, but projecting beyond the ends of the beams 13. The inner ends of each pair of said rafters are secured to the top ends of posts 16 (only one of which is shown in Figs. 2 and 3) which in turn are secured to the cross beams 13.

The rafters of each pair of rafters 15, are connected together at their outer or bottom ends and inner or top ends, by longitudinally extending angle bars 17 and 18, and at a point intermediate said ends by longitudinally extending angle bars 19 and 20 respectively. The angle bars 20, are connected together by transverse, horizontal tie bars 21, which in turn are secured at their middle to the posts 16.

The outer angle bars 17 and the intermediate angle bars 19, are connected together by inverted T-shaped glazing bars 22, while the inner angle bars 18 and the intermediate angle bars 20 are connected together by similar glazing bars 23, said glazing bars being parallel with but arranged in

a plane above the rafters 15. Between the intermediate angle bars 19 and 20, I provide longitudinally extending combination sealing and gutter strips 24, of sheet metal (see Figs. 2, 3 and 7). Said strips each includes angularly disposed body parts 25 and 26 respectively. The body part 25 of each strip is engaged against one flange of each angle bar 19 and includes an outwardly and downwardly bent flange 27 which embraces and encloses the top margin of said flange of said angle bar, while the body part 26 of said strip extends away from said angle bar and has its margin bent back upon itself as shown in said figures. Openings 28 are provided in said body part 26 of said strips, the purpose of which will appear later. A layer of putty 29 or other waterproof cementitious filler (see Fig. 3) is interposed between the body part 25 of each of said strips and the associated intermediate angle bar 20.

30—30 indicate eaves gutter strips, which close the spaces between the outer angle bars 17 and the curb walls 11 of the sides of the skylight. Each eave strip (see Fig. 9) includes an upright web 31, which has oppositely disposed top and bottom flanges 32—33. Made integral with the outer margin of the bottom flange 33 is an outwardly and upwardly inclined flange 34, which terminates in an inturned hook 35, said hook being adapted to engage with clips 36 secured to the angle bars 17 at points between the glazing bars 22 (see Figs. 4 and 5). When the eaves strips are in place, the top flanges 32 engage upon the top surfaces of the side walls of curb 11, with the upright webs 31 engaged against flashing strips 37 providing the water-proof connection between the outer surfaces of the curb walls, and the top surface of the roof 10. The angular flanges 34 of said eaves strips are secured to the outer surfaces of the angle bars 17, with the hook flanges arranged in a plane above said angle bars and engaging the clips 36 as before described. As shown in Figure 3, the bottom flanges 33 bridge and close the spaces between said curbs and angle bars 17, and in said bottom flanges are longitudinally spaced drain openings 38.

40 indicates as a whole, a single sheet metal ridge piece or cap bent into suitable inverted channel shape and adapted to close the open space between the angle bars 18 at the ridge of the skylight (see Figs. 1, 2, 3 and 8). This ridge piece or cap includes oppositely disposed, downwardly and outwardly inclined top parts 41, which are bent inwardly and back upon themselves to form double thickness flanges 42. The inner or bottom folded parts of said flanges are then bent at right angles to provide converging flanges 43, and then outwardly to provide webs 44 parallel with the flanges 42, said

webs terminating at their outer margins in converging flanges 45 offset from but parallel with the flanges 43. As will be apparent from Fig. 8, the flanges 42 and 43, and the webs 44, provide longitudinally extending, outwardly opening grooves 46 in the sides of said ridge strips, the purpose of which will appear later. When this ridge strip is in place, it will set with the flanges 45 thereof, in engagement with the top angle bars 18, as clearly shown in Figure 3.

Panels 50, preferably of glass, are supported on the flanges 22 of the glazing bars 22, and layers or pads of putty or other waterproof cementitious material 51 (see Fig. 4) is interposed between the side margins of said panels and said flanges of said glazing bars to prevent water leakage at the side margins of the panels 50. Interposed between the ends of said panels and the adjacent parts of the skylight structure are putty layers or pads 52 (see Figs. 3 and 5). The top surfaces of said panels 50 are flush with the top surfaces of the hook flanges 35 of the eaves strips 30, for the shedding of water from the top surfaces of said panels.

Panels 53 of glass are supported on the glazing bars 23, in a similar manner with putty layers or pads 54 (see Fig. 3) providing the water-tight connection between the side margins of the panels and the associated flanges of the glazing bars 23. The panels 53 are of a length greater than the distance between the angle bars 18 and 20, so that the top inner ends of said panels extend into the grooves 46 of the ridge strip 40 and engage upon the webs 44 of said ridge piece, as shown in said Fig. 3, and thus assist in locking said ridge strip in place.

To hold the panels 50—53 against vertical displacement, I provide the following construction. Engaged with the opposite surfaces of the upright web of the glazing bars 22—23, are thin metallic glazing or locking strips 55 (see Fig. 4) each having an outwardly and downwardly bent flange 56 which terminate adjacent the margins of said panels. These strips are held in place by pins 57 which extend through holes 58 in said upright webs of the glazing bars, and which are bent over at their ends to engage the top marginal parts of the said strips. The top marginal parts of the vertical web of the glazing bars as well as the angular flanges 56 of the strips 55 are enclosed or covered by inverted V-shaped cover strips 59 having inwardly bent hook flanges 60, that engage between the bottom edges of the flanges 56 and the top surfaces of the marginal parts of the panels. The inner top end of the cover strips 59 associated with the glazing bars 22 engage beneath the bent over flange 27 of the combination seal-

ing and gutter strips 24, while the inner top ends of the cover strips 59 associated with the glazing bars 23 extend into the grooves 46 of the ridge strip and engage beneath the bent over double flanges 42 of the same.

Removably attached beneath and parallel with each of the glazing bars 22 and 23 are removable condensation gutter strips 61 and 62 respectively. Each of said strips is of substantially shallow V-shaped cross section, and has marginal flanges 63 which are bent inwardly upon the side walls of said strips. The gutter strip 61 (see Fig. 3) associated with each glazing bar 22, is of a length equal to the distance between the inner surface of the angle bars 17 and the bent over marginal edge of the combination strips 24 before referred to and the outer end of said condensation strips are cut away so as to discharge into the eaves strips 30. Short sections of the flanges 63 of said strips are bent upwardly and away from the body parts of the strips to provide oppositely disposed ledges 64 adapted for hooked engagement upon clip fingers 65 secured to the under surface of those flanges of the angle bars 17 which rest upon the top surface of the rafters 15. Near the opposite end of the gutter strips 61, other short sections of said flanges 63 are bent upwardly away from the body of the strip, to provide another pair of oppositely disposed ledges 64^a adapted for hooked engagement upon similar clip fingers 65^a on the angle bars 19, said fingers being duplicates of the fingers 65 on the angle bar 17. The condensation gutters 62 associated with the glazing bars 23 are of a length, shorter than the distance between the angle bars 18 and 20, but have similar bent out sections of flanges 63 to provide similar ledges 64—64^a which engage upon clip fingers 65—65^a on the angle bars 20 and 18 respectively. The outer end of the condensation gutter strips 62 overhang the flange 26 of the combination strip 24 and are cut away in the same manner as the strips 61, to discharge any water of condensation, onto the flange 26 of said combination strip 24. Such water will pass through the holes 28 in the flanges 26 and into the gutter strips 61, which in turn discharge by gravity into the eaves strips 30 which have the holes 38 for discharging said water upon the roof outside the skylight. This construction of condensation strips 61 and 62 permits attachment and removal without the aid of tools, for the purpose of cleaning and painting.

After the skeleton structure of the skylight, which comprises the beams 13 and rafters 15, together with the angle bars 17, 18, 19 and 20, and the cross bars 21 and

glazing bars 22—23 have been erected, the ridge piece 40 is placed in position with its flanges 45 engaging and resting upon the angle bars 18. The clips 36 are then placed on the angle bars 17 between the glazing bars 22, and engaged with the hooked flanges 35 of the eaves strips 30, which of course have been engaged upon the curbs 17 before the beams 13 were set in place. Of course the combination strips 24 are placed in position between the angle bars 19 and 20 and the putty layer 29 applied at the time of setting the angle bars 19 and 20.

The glazing or locking strips 55 are then secured in place to the glazing bars and the putty applied thereto for the side margins of the panels. The panels 53 are then inserted in place with their top ends extending into the grooves 46 of the ridge piece, and engaging the webs 44 of said ridge strip, and thus lock said strip in place. The inverted V-shaped cover strips 59 are then applied to the glazing bars 23 and strips 55 from the outer end thereof, and moved longitudinally upward and inward until the top ends of said cover strips engage beneath the double flanges 42 of the ridge strip. The slight resiliency in the flanges 42 of the ridge strip together with the engagement of the cover strip with the side strips of the glazing bars holds the cover strips in position.

The panels 50 are then placed in position on the glazing bars 22 and the cover strips 59 applied thereto in the same manner as in the case of the cover strips 59 before mentioned. The cover strips associated with the glazing bar 22 are engaged at their top inner ends, beneath the bent over flange 27 of the combination strips 24 and this assists in holding said cover strips in place. The condensation gutters 61—62 are now placed in position with the ledges 64—64^a thereof aligned with the clip fingers 65—65^a after which an endwise outward movement of said condensation strips will cause the said ledges to removably engage upon the top surface of said fingers, so as to be supported thereon, the said strips being limited in their outward movement by their engagement with the angle bars 17 and 20 respectively. To remove the said condensation strips, they are moved inwardly away from the angle bars 17 and 20 when they become disengaged from the clip fingers which support them.

It is apparent that water will readily drain from the outer surface of the skylight. Such vapor as condenses on the inner surfaces of the top panels 53 will drain into the combination strips 24 and then into the condensation strips 61 to discharge into the

eaves strips 30 and then out through the cover strip enclosing the web and having in-holes 38 in the same, to the roof. Such vapor as condenses on and drops from the glazing bars, 22-23 falls into the gutter 5 strips to be discharged outside the skylight in the same manner.

The parts embodied in the skylight construction are so arranged as to interlock with and brace one another, and any one of the panels may be removed without materially disturbing the adjacent parts. The glazing bar condensation strips may be quickly removed and replaced when it is desired to paint or clean the skylight.

15 While in describing my invention I have referred to certain details of mechanical construction, form and arrangement of parts, I do not wish to be limited thereto except as may be pointed out in the appended claims.

I claim as my invention:—

1. In a skylight construction, the combination of a frame including glazing bars, panels supported on said glazing bars, 25 finger clips secured to the frame in line with the glazing bars, and condensation gutters having side flanges, including parts bent to form ledges, which removably engage said finger clips.

20 2. A condensation gutter for a skylight comprising, a strip of sheet metal bent into a V-shape channel, having side walls, the top margins of said side walls being folded inwardly upon themselves to form flanges, parts of which are bent away from the side walls to extend into substantially the same plane and provide attaching ledges.

35 3. In a skylight construction, including glazing bars of inverted T-shaped members, having an upright web and laterally extending flanges, panels supported on said lateral flanges, a sealing strip engaged with each side of the web of said inverted T-shaped members, each sealing strip being shorter in height than the web and including an outwardly and downwardly extending flange which overhangs the associated margin of the panels, means carried by said upright web above said sealing strips for securing them in place on said glazing bars, and a

55 cover strip enclosing the web and having in-holes which engage between the flanges of both sealing strips and the margins of said panels.

4. In a skylight construction, including glazing bars of inverted T-shaped members, having an upright web and laterally extending flanges, panels supported on said lateral flanges, a sealing strip engaged with each side of the web of said inverted T-shaped members, each sealing strip being shorter in height than said web and including an outwardly and downwardly extending flange which overhangs the associated margin of the panels, pins adapted to be inserted through the web of said glazing bar above the sealing strips, to engage and lock the same to said glazing bar, and an inverted V-shaped cover strip having inturned hook flanges, enclosing said web of the glazing bars and the sealing strips, which hook flanges engage between the flanges of the sealing strips and the margins of the panels.

5. In a skylight construction, the combination of outwardly and downwardly converging rafters, longitudinally extending top, bottom and intermediate frame bars, the intermediate frame bars being arranged in pairs, a combination sealing and gutter strip 75 between the intermediate frame bars, glazing bars connecting said frame bars, panels supported on the glazing bars, condensation gutter strips arranged in sets and supported on said frame bars beneath said glazing bars, eaves strips having water discharge 80 openings associated with the bottom frame bars, one set of gutter strips discharging into the combination strip which in turn discharges into the second set of condensation strips, said last mentioned set of condensation strips discharging into the eaves strips.

In testimony that I claim the foregoing as my invention, I affix my signature in the presence of two witnesses, this 24th day of November, A. D. 1920.

JOSEPH SYLVAN.
